Application September 26, 1942, Serial No. 459,809

6 Claims. (Cl. 236—35)

My invention relates to controlling structure for oil coolers such as are used in connection with hydrocarbon engines, such as aircraft engines, for keeping the lubricating oil in the most desirable condition for efficient lubrication under the varying temperature conditions encountered. The invention relates particularly to improved valving assembly for controlling the oil flow through the cooler forming jacket and radiator, and for controlling the flow of oil to and from a cylinder structure which operates shutters provided on the cooler.

My invention may be considered as embodying improvements over the oil cooler controlling structure disclosed in my pending application Serial No. 453,299, filed August 1, 1942.

In my present application, the structure for controlling the flow of the oil through the cooler is substantially the same as that in my pending application, and under normal conditions, like in my pending application, the operation of the shutter controlling cylinder structure is controlled by the pressure of the flow through the cooler.

An important object of my present invention is to provide further control of the fluid flow for the shutter operating cylinder structure in the form of thermostat controlled means responsive to the temperature of the flow through the cooler in such manner as to prevent closing or opening of the shutters during increase or decrease of the rate of flow through the cooler.

Another important object is to provide a control for fluid flow to the shutter controlling cylinder structure involving a relief valve and a thermostatically operated valve in parallel therewith, with the relief valve, upon closure of the thermostatically controlled valve, being responsive only to a predetermined pressure built up in the cooler to open up for flow of fluid to the cylinder structure, and with the thermostatically controlled valve operating in response to temperature to open for free flow to the cylinder structure for opening or closing movement of the shutters.

The above referred to and other features of my invention are embodied in the structure shown on the drawings, in which drawings—

Figure 1 is a side elevation, partly in section, of an oil cooler with my improved valving assembly mounted thereon;

Figure 2 is an enlarged section on plane II—II of Figs. 1 and a section on plane II—II of Fig. 3, but with the piston at the inner end of the cylinder.

Figure 3 is a section on plane III—III of Fig. 2

but with the piston at the outer end of the cylinder;

Figure 4 is a section on plane IV—IV of Fig. 3;

Figure 5 is a section on plane V—V of Fig. 3;

Figure 6 is a section on plane VI—VI of Fig. 3;

Figures 7 to 13 inclusive are sections on plane VI—VI of Figs. 2 and 3 of the controlling valving assembly for the cylinder structure showing the assembly in various positions during operation of the structure.

Referring to Fig. 1, R indicates the radiator structure and V the valve structure. The radiator structure shown is of a conventional type, comprising the cylindrical shell 10 through which 15 extend the tubes 11 soldered or otherwise secured together at their ends and exposed for flow therethrough of air during running of the vehicle or airplane. Surrounding the shell 10 is the warming jacket 12 which is connected at its lower side 20 with the radiator through a passage 13. Mounted on top of the warming jacket is the base plate 14 on which the valve structure V seats and is secured as by screws 15.

Referring to Figs. 2 to 6, the valve structure V 25 comprises the housing 16 having the inlet 17 for the oil from the engine E, and the outlet 18 for return flow from the radiator and warming jacket to the sump O from which the oil to the engine is delivered by a pump P (Fig. 1). Within the 30 housing at opposite sides of the inlet 17 are the transverse walls 20 and 21 between the sides and top of the housing. The lower ends of the transverse walls are connected by the horizontal wall 22 extending between the sides of the housing. 35 The walls 20, 21 and 22, together with the sides and top of the housing 16 define a valve chamber 24. Partly surrounding the walls which define the valve chamber 24 is the inlet space 28, the outlet passageway 29 from which registers with 40 the passageway 30 through the base 14 on the warming jacket, the jacket having the inlet 31 communicating with the passageway 30.

The wall 20 has the passageway 32 therethrough 45 for connection of the valve chamber 24 with the space 33 with which the outlet 18 communicates. The passageway 32' in the wall 21 serves to connect the valve chamber with the space 28. Within the valve chamber 24 is a valving assembly comprising the annular valve 34 for closing the passageway 32, and the annular valve 35 for closing the passageway 32'. Between these valves is a thermostat T which may be of the type known in the trade as the "Vernet" type. The thermostat comprises the body or container 36 from which 50 the neck 37 extends which receives the plunger

38 to be acted upon by the thermostatic material within the container which, upon expansion due to rising temperature, will exert pressure against the plunger 38 to shift the container toward the left (Fig. 2), the plunger at its outer end abutting an adjustable abutment 39 mounted in the adjacent end wall of the housing 16.

The neck 37 extends axially through the valve 35 and has rigidly secured thereto a collar 49 which has a spherical surface against which the valve 35 is normally held by a spring 41. Formed on the inner end of the thermostat body is a stud 42 to which is rigidly secured a sleeve 43 which at its inner end has a shoulder 44. Slidably mounted on the sleeve is the annular relief or blowoff valve 45 which seats on the outer side of the valve 34. The valve 34 has fingers 46 for engaging the shoulder 44 on the sleeve 43 to be normally held in this position by the spring 41 between the valves 34 and 35. A spring 47 engages against the outer side of the blowoff valve 45, a cage 48 extending from the wall 20 forming the abutment for the outer end of the spring. The spring 47 is weaker than the spring 41 and the valves 34 and 35 are therefore normally held in seating engagement to close the passageway through the valve 34. This unitary assembly comprising the thermostat T, the valves 34, 35 and 45 and the spring 41 is shiftable axially by the thermostat, the axial movement being guided by guide wings 49 on the valves 34 and 35. The thermostat T is adjusted so that at temperature below, say 100° F., the thermostat will be in its contracted position shown on Fig. 3, the valve 34 being open and the valve 35 closed, the spring 47 effecting such shift of the assembly. As the thermostat is subjected to higher temperatures, the material therein will expand, and as the spring 41 is stronger than the spring 47, the thermostat body with the valves thereon will be shifted away from the plunger 38 toward the left for opening of the valve 35 and closing of the valve 34 to the position shown on Fig. 2. The thermostat may continue to expand after the valve 34 has been seated and, unless means were provided to allow such overtravel, the thermostat body might burst. To permit overtravel without fracture, the sleeve 43 attached to the thermostat body slides to the left within the blowoff valve 45, the shoulder 44 on the sleeve leaving the fingers 46 on the valve 34, the valve 34 being then seated by the spring 41 to close the passageway 32 and the valve 35 being moved by the spring 41 to the left beyond its normal fully open position until the overtravel of the thermostat ceases.

Referring to Figs. 3 and 5, a horizontal wall 50 extends inwardly from the left end wall of the housing 16 and transversely between the side walls of the housing. A cylindrical wall portion 51 extends between the wall 50 and the top wall 52 of the housing to provide a seat for a cylinder 53, the axis of this cylinder being parallel with but to one side of the axis of the valve assembly in valve chamber 24. At its outer end the cylinder has the flange 54 engaging against the adjacent left end of the housing 16, the outer end of the cylinder being closed by a head 55 between which and the end of the housing 16 the cylinder flange 54 extends to be clamped as by screws 56 threading into flanges 57 on the housing (Fig. 4).

Referring to Figs. 3 and 6, an annular valve seat 58 is secured in the bottom wall of the housing 16 between the inner end of the cylinder 53 and the wall 20 of the valve chamber 24. The

passageway 59 through the valve seat 58 communicates with the passage 66 through the base 14 on the warming jacket 12, the warming jacket outlet 61 registering with the passageway 66. Between the warming chamber inlet 31 and the outlet 61 a partition wall 62 extends transversely across the warming jacket so that oil flow into the inlet 31 must travel circumferentially around the warming jacket before reaching the outlet 61.

To the left of the valve seat 58, Figs. 3 and 5, a valve seat 63 is secured in the bottom wall of the housing 16 with its passageway 64 in alignment with the radiator outlet nipple 65 which extends into the passageway 66 in the base 14.

A valve 67 is engaged by a spring 68 tending to hold it seated against the inner side of the seat 58, a cage 69 anchored to the seat 58 forming the abutment for the outer end of the spring. A similar valve 70 is engaged by a spring 71 tending to hold it seated against the inner side of the seat 63, a cage 72 anchored to the seat forming the outer abutment for the spring, the spring 71 being lighter than the spring 68.

The operation of the structure thus far described is as follows. Before the engine is started, the temperature is usually such that the thermostat T is contracted, as shown on Fig. 3, the valves 34 and 35 being respectively open and closed.

The thermostat is adjusted to remain contracted under say 100° F., and as the engine now starts, the pump D driven thereby will draw oil from the sump O and force it through the engine bearings, the oil flowing from the engine into the inlet 17

around the valve assembly and past the open valve 34 through the passageway 32 into the space 33 and from there directly back through the outlet 18 to the sump (Fig. 1). This permits rapid warming of the oil in the sump since it

receives no cooling flow from the radiator. The warmed oil, engaging with the thermostat element T, raises the temperature thereof above 100° F. to actuate the thermostat to open the valve 35 and to close the valve 34 so that oil may

then flow into the inlet space 28 for flow into the warming jacket through the inlet 31. Usually the oil is sluggish in the cooler before the engine is started, and a pressure is built up in the valve chamber which, together with the warm oil, will soon force flow of the oil through the jacket.

The built up pressure will be against the valve 68 which is set to remain closed until a pressure, say of 30 lbs. per sq. in., is reached, and when the valve opens, the flow through the warming jacket will begin, the discharged oil flowing through the outlet 18 back to the sump. During this time some oil may be forced from the jacket through the inlet passageway 13 and through the radiator and past the valve 70 whose spring 71 is comparatively light. This light flow through the radiator assists in the warming thereof and as the radiator warms and the resistance to flow through it decreases, the rate of flow increases until a temperature, say 180° F. is reached, the pressure through the jacket then dropping down below 30 lbs. per sq. in. so that the spring 68 closes the valve 67, all of the oil then flowing through the radiator. Should the oil in the radiator suddenly become sluggish or congeal, pressure will again build up in the jacket until the radiator has again become warmed up for normal flow therethrough.

Should the oil in both the radiator and the warming jacket suddenly congeal while the valve 34 is closed by the thermostat, the built up pressure in the valve cham-

ber will again force flow through the jacket, the radiator and the warming jacket suddenly congeal while the valve 34 is closed by the thermostat, the built up pressure in the valve cham-

ber 24 will open the blowoff valve 45 for flow of the engine oil through the passageway 32 and outlet space 33 and back to the sump until the pressure built up by the oil from the engine can reestablish flow through the jacket.

Describing now the shutter controlling mechanism, a piston 73 within the cylinder 53 has the rod 74 extending therefrom through the cylinder head 55, the rod being connected through linkage 75 anchored at 75, with the bar 76 connected with the shutters 77 on the radiator R. The piston rod has the bore 78 into which extends the head 79 of the cylindrical valve bar 80. The valve bar extends through the inner wall 81 of the cylinder to which it is connected by threading 82 to be substantially held against axial movement relative to the cylinder but to be rotatable. The valve bar head 79 has diametrically opposite longitudinally extending helical grooves 83 and 84 in which engage the ends of fingers 85 and 86 projecting radially inwardly from a ring 87 secured to the inner side of the piston 73, as by rivets 87'. Due to the connection of the piston rod with the shutter operating linkage 75, the piston is held against rotational movement in the cylinder 53 but, as the piston moves inwardly and outwardly in the cylinder, the cam fingers 85 and 86 engaging in the helical grooves will cause corresponding rotational movement of the valve bar. The pitch of the grooves is comparatively small so that for a complete inward or outward movement of the piston the valve bar will be rotated through a comparatively small angle, say about 25°.

The inner end of the valve bar 80 projects through the wall 20 into the valve chamber 24 (Figs. 2 and 4) and the valve bar has the bore 88 therethrough for flow of fluid from the valve chamber. A cross wall in the bore has a passageway 89 therethrough and on its outer side provides a seat for a ball valve 90. Threading into the outer end of the bore 88 is an abutment plug 91 between whose inner end and the valve 90 is interposed the spring 92 which tends to hold the valve 90 seated to close the passageway 89.

A spring assembly 93 in the cylinder 53 tends to shift the piston 73 to its inner position shown on Fig. 2, ports 94 in the valve bar serving to connect the valve bore with the inner end of the cylinder 53 behind the piston so that, upon flow of oil under pressure through the valve bar bore and into the cylinder, the piston will be shifted outwardly for actuation of the linkage assembly 75 to cause closing movement of the radiator shutters.

Just inside the passageway 89 controlled by the valve 90, one or more ports are provided in the valve bar, two such ports 95 and 95' being shown diametrically opposite. Adjacent to the outer side of the passageway 89 the bar has the diametrically opposite ports 96 and 96'. Receiving the valve bar is a valve collar 97 rotatable on the bar but held against axial movement by being located between the inner wall of the cylinder 53 and a snap ring 98 surrounding the valve bar. The rotary movement of the valve collar is controlled by a thermostat 99, shown in the form of a spiral, having one end anchored to the valve collar and the other end anchored to a lug 100 on the inner wall of the cylinder 53.

The valve collar has the two diametrically opposite longitudinally extending ports 101 and 101' adapted, during certain settings of the valve collar, to connect respectively the valve bar ports

95 and 96 and 95' and 96', and the valve collar during other settings shuts off flow through these ports. When the valve bar ports are closed by the valve collar, there can be no fluid flow through the valve bar bore to the cylinder until the pressure in the valve chamber 24 is sufficient to cause unseating of the valve 90 against the resistance of the spring 92. However, when the valve collar is set for registration of its ports with the valve bar ports, fluid may flow from the chamber 24 through the valve bar bore around the valve 90 and into the cylinder.

By means of the threaded abutment 91 in the outer end of the piston rod, the desired tension of the spring 92 may be adjusted for, and this abutment has the bore 102 therethrough so that oil under pressure may flow from the valve chamber 24 through the valve bar 80 and through ports 94 into the cylinder behind the piston, and also through the bore 102 of the abutment member and against the outer wall of the piston rod, so that maximum piston surface is available for the fluid to effect outward movement of the piston against the resistance of the springs 93, for closure movement of the shutters. Upon outward movement of the piston, the oil in the outer part of the cylinder may escape through the passageway 103 into the outlet space 33 which is connected through the outlet 18 with the sump O. Upon cessation of fluid flow from the valve chamber 24 through the valve bar into the cylinder, or upon decrease in pressure in the valve chamber 24, and corresponding inward movement of the piston by the spring assembly 93, the oil may escape from the inner end of the cylinder by way of a relief passage 104 through the inner wall of the cylinder (Fig. 3), and some of this oil may also escape along the threading 82 into the outlet space 33. So long as the pressure of the flow from the valve chamber 24 into the cylinder balances the pressure of the springs 93 and the outflow of oil from the inner end of the cylinder, inward movement of the piston will be stopped and the shutters held in a corresponding open position.

Describing now the operation of the shutter controlling mechanism, before the engine is started and the oil in the cooler is sluggish or more or less congealed, the warm oil from the engine flows into the valve chamber 24 and out past the open valve 34 into the outlet space 33 and through the outlet 18 directly back to the sump, the thermostat T soon becoming heated to shift its valve assembly for closure of the valve 34 and opening of the valve 35, the valve ports 95, 95' and 96, 96' being then closed by the valve collar 97, as shown clearly on Fig. 7. The spring 68 controlling the outlet valve 67 from the warming jacket is dimensioned so that it will not open until a pressure of say 30 lbs. per sq. in. is reached. The flow through the jacket being sluggish, the incoming engine oil will build up a pressure in the valve chamber 24 and as soon as this pressure reaches 30 lbs. per sq. in., the valve 90 in the valve bar will be unseated against its spring 92 which is set to resist opening of the valve until a pressure of 30 lbs. per sq. in. is reached. Upon opening of the valve 90 fluid will flow from the valve chamber 24 through the passageways 89 and ports 94 into the cylinder for quick outward movement of the piston to close the shutters and then the oil in the warming jacket and in the radiator is quickly warmed up for freer flow and under pressure less than 30 lbs. per sq. in. so that the valve 67 will be closed by its spring 68 and

all of the fluid will eventually be through the radiator past the valve 70 which is resisted by the comparatively light spring 71. The thermostat controlling the valve collar 97 is in the path of the oil flow from the cooler through the outlet space 33 and outlet 18 to the sump.

As the piston was shifted out to close the shutters, the action of the fingers 85 and 86 on the piston in the helical grooves 83 and 84 in the valve bar caused rotation of the valve bar in counterclockwise direction to the position shown on Fig. 8, with its ports displaced, say 25°, from the position of the ports shown on Fig. 7 when the piston was in. Immediately after reduction of the pressure in valve chamber 24 below 30 lbs. per sq. in., the valve 90 is closed by its spring 92 but the thermostat 99, in response to the temperature of the oil flowing from the warming jacket, turns the valve collar in clockwise direction to bring its ports 101 and 101' into registration with the valve bar ports, as shown on Fig. 9, so that, after closure of the valve 90, the fluid flow from the valve chamber 24 is through the valve bar ports and the valve collar ports into the cylinder behind the piston and the piston will be held out to keep the shutters closed, pressure much less than 30 lbs. per sq. in., say as low as 8 lbs. per sq. in., in the valve chamber 24, being sufficient to hold the piston out.

The rotation of the valve collar to bring its ports into registration with the valve bar ports takes place while the temperature rises to say near 140° F. Figs. 3 and 6 shows the arrangement of the parts corresponding with Fig. 9, except that the valve assembly controlled by the thermostat T will be in position to close the valve 34 and open the valve 35.

As the temperature now increases the valve collar will continue to rotate and will move its ports away from the valve bar ports, as shown on Fig. 10, and as soon as the ports move out of registration, further flow from the valve chamber 24 into cylinder will stop, as at this time the pressure is below 30 lbs. per sq. in. and the valve 90 is closed. With the flow of fluid into the cylinders behind the piston stopped, the springs 93 become effective to move the piston inwardly for movement of the shutters toward open position so that cooling air may flow through the radiator. As the piston is moved inwardly by the springs, the fluid at the inner end of the cylinder flows gradually through the more or less restricted relief outlet 104, and some of the oil will escape past the threading 82 and some oil may also leak past the piston. Upon such inward movement of the piston, the engagement of the piston fingers 85 and 86 in the valve bar helical grooves will cause rotation of the valve bar in clockwise direction to follow the turning movement of the valve collar. If the temperature keeps rising, the valve collar will continue to move its ports away from the valve bar ports so that the piston may move entirely inwardly for complete opening of the shutters. Figs. 2 and 11 shows the arrangement of the ports when the temperature reaches say 180°, and this temperature may be the temperature desired for normal running conditions and, when this temperature is reached, the valve collar 97 will have been rotated 180° from the position shown in Fig. 7. Should the temperature decrease, the thermostat 99 will rotate the valve collar back in counterclockwise direction, as shown on Fig. 13, to bring its ports back into registration with the valve bar ports, so that oil may flow from the valve chamber 24 into the

cylinder to shift the piston out for closing movement of the shutters to reduce the air flow through the radiator. During such outward movement of the piston the valve bar will be rotated in counterclockwise direction. Referring to Fig. 13, if the temperature at the thermostat 99 decreased to, say 140°, and remained there, and the collar were shifted due to this temperature change to just bring its ports into registration with the valve bar ports, then the fluid flow from the valve chamber 24 into the cylinder will move the piston out and the accompanying rotation in counterclockwise direction of the valve bar will move the valve bar ports out of registration with the valve collar ports and further flow from the valve chamber 24 will stop, and if the temperature decreases further, the valve collar ports will again come into registration with the valve bar ports for further outward movement of the piston and corresponding further movement of the shutters. However, as soon as the temperature increases and the valve collar is rotated in clockwise direction, its ports will cooperate with the valve bar ports for full opening of the shutters when the temperature again reaches 180°. Thus the pressure of the cooler oil flow and the temperature thereof will cooperate to control the piston operation for setting of the shutters for proper operation of the radiator.

If, while the temperature in the control assembly is at normal, say 180°, the airplane suddenly climbs into subzero temperature and the oil in the cooler is therefore suddenly congealed, the pressure in the valve chamber 24 will rapidly rise to 30 lbs. per sq. in or over, and, as at 180° temperature within the control assembly the valve collar shuts off the valve bar ports, this built up pressure will force open the valve 90 for flow of oil from the valve chamber 24 into the cylinder to quickly move the piston out for closure of the radiator shutters (see Fig. 12). Owing to the sudden congealing of the oil in the cooler, the built up pressure may rise beyond 30 lbs. per sq. in. in which event the blowoff valve 45 in the valve chamber 24 will open up against the resistance of the spring 47, which resistance may be say 75 lbs. per square inch. The oil from the engine will then flow directly back to the sump until the pressure has been sufficiently reduced for reclosing of the blowoff valve. After closure of the shutters by the piston, the pressure and temperature of the oil from the engine will soon thaw out the cooler for flow therethrough and reduction of the pressure below 30 lbs. per sq. in. so that the valve 90 will close and the spring 93 will return the piston and shutters to the position decreed by the angular setting of the valve collar by the thermostat 99.

It may be desirable to adjust the setting of the thermostat 99 and the valve collar relative to the valve bar. As shown this is accomplished by rotating the cylinder 53 to which one end of the thermostat is anchored. As shown in Fig. 2, the cylinder flange has the extension 185 projecting outwardly so that, after loosening of the screws 56, the cylinder may be rotatably set for the desired setting of the thermostat, and after such setting the screws 56 are retightened.

If, during normal operation of the cooler at say 180°, the rate of oil flow from the engine through the cooler is increased with corresponding increase of pressure in the valve chamber 24, this pressure cannot effect closing movement of the shutters because the valve 90, and the setting of the valve collar by the thermostat, shuts off flow

from the valve chamber to the cylinder. Unless this increase in pressure due to increasing rate of flow reaches 30 lbs. per sq. in., which is very unlikely, the valve 90 will remain closed.

Although a pressure of 30 lbs. per sq. in. in the valve chamber 24 may be required to open the valve 90 for oil flow into the cylinder, a much less pressure, say for example 8 lbs. per sq. in., in the valve chamber will be sufficient to hold the piston in its outer position for closure of the shutters. Such closure of the shutters is usually during a warming up period for bringing the cooler oil to its normal temperature of 180°, and during such warming up period, as indicated on Fig. 9, the thermostat will set the valve collar for exposure of the valve bar ports for oil flow to hold the piston out with the shutters closed. If now, during this warming up period, the rate of flow from the engine should decrease with corresponding decrease in pressure in the valve chamber 24, such decrease would have to be less than 8 lbs. per sq. in., which is very unlikely, and the piston will therefore be held in its out position and opening of the shutters prevented. Toward the end of the warming up operation the thermostat 99 will set the valve collar to shut off flow through the valve bar ports and then the inward movement of the piston for opening of the shutters will be controlled in a manner hereinbefore explained.

I have shown a practical and efficient embodiment of the features of my invention but I do not desire to be limited to the exact construction, arrangement and operation shown and described, as changes and modifications may be made without departing from the scope of the invention.

I claim as follows:

1. A controlling structure for an internal combustion engine oil cooler having shutters thereon, comprising a housing having an inlet chamber for receiving the oil from the engine for delivery to the cooler, a cylinder having a piston connected with the cooler shutters for operation thereof, spring means tending to move said piston inwardly for opening movement of the shutters, a valve member in the form of a bar between said inlet chamber and said cylinder and having a bore therethrough for the flow of oil from the chamber to the cylinder, a spring pressed check valve in said bore closing said bore against flow therethrough under normal fluid pressure in said inlet chamber but being responsive to predetermined increased pressure to open said bore for flow of fluid to the cylinder to effect outward movement of the piston for closing movement of the shutters, ports at opposite sides of said check valve extending from said valve bar bore to the exterior thereof, a valve collar movable on said valve bar and having ports to be brought into registration with said valve bar ports to afford flow passageway from the inlet chamber to the cylinder when said check valve is closed, and a thermostat subjected to the temperature of the discharge oil from the cooler for setting said valve collar in accordance with variations in temperature to open or close said valve bar ports whereby the movement of said piston and shutters will be in accord with the pressure in said inlet chamber and the temperature of the discharge cooler oil.

2. A controlling structure for an internal combustion engine oil cooler having shutters thereon, comprising a housing having an inlet chamber for receiving the oil from the engine for delivery to the cooler, a cylinder having a piston connected with the shutters for control thereof, spring means tending to move said piston inwardly for

opening of the shutters, a valve member in the form of a bar between said inlet chamber and said cylinder having a bore therethrough for flow of oil from the inlet chamber into the cylinder behind the piston, a spring pressed check valve in said bore closing said bore against flow into the cylinder under normal fluid pressure conditions but opening said bore under predetermined increased pressure conditions for flow of oil into the cylinder for outward movement of the piston, ports on opposite sides of said check valve extending from said valve bar bore to the outer side thereof, a valve collar rotatable on said valve bar and having ports for registering with said valve bar ports for flow of oil from the inlet chamber into the cylinder when said check valve is closed, a camming connection between said piston and said valve bar effective during axial movement of the piston to rotate said valve bar for setting of its ports relative to said valve collar ports, a thermostat for rotating said valve collar in accordance with variation in temperature of the oil discharged from the cooler for setting of said collar ports relative to said valve bar ports, whereby the rotational movements of said valve bar and valve collar will control the connection or disconnection of the valve bar ports and the valve collar ports and the movement of said piston and the shutters will be in accord with the pressure in said inlet chamber and the temperature of the discharged cooler oil while said check valve is closed.

3. A controlling structure for an internal combustion engine oil cooler having shutters thereon, comprising a housing having an inlet chamber for receiving the oil from the engine for delivery to the cooler, a cylinder having a piston connected with the shutters, a duct for flow of oil from the inlet chamber into the cylinder, a spring pressed check valve in said duct shutting off flow therethrough under normal pressure conditions in said inlet chamber, a by-passageway around said check valve for flow of oil to said cylinder when said check valve is closed, a control valve for said by-passageway rotatable on said duct, and thermostat means for setting said control valve in accordance with the temperature of the discharged cooler oil, said thermostat means under comparatively low temperature setting said control valve for closure of said by-passageway, said check valve during closure of said by-passageway being responsive to abnormal pressure increase in said inlet chamber to open passageway through said duct for flow of oil for moving said piston for closure movement of the shutters.

5. A controlling structure for an internal combustion engine oil cooler having shutters thereon, comprising a housing having an inlet chamber for receiving the oil from the engine for delivery to the cooler, a cylinder having a piston connected with the shutters, a duct between said inlet chamber and said cylinder for fluid flow to said cylinder and operation of said piston to control the shutters, a check valve in said duct and a spring for holding it closed against flow therethrough under normal pressure in said chamber, a by-passageway around said check valve for flow of oil to said cylinder when said check valve is closed, a control valve for said by-passageway surrounding said duct, and thermostat means for setting said control valve in accordance with the temperature of the cooler oil discharge flow to open or close said by-passageway, said check valve during closure of said by-passageway by said control valve responding to predetermined pressure increase in said chamber to open said duct

for flow to the cylinder for movement of the piston to close the shutters.

5. A controlling structure for an internal combustion engine oil cooler having shutters thereon, comprising an inlet chamber for receiving the oil from the engine for delivery to the cooler, a cylinder having a piston therein connected with the cooler shutters for control thereof, spring means tending to shift said piston for opening of the shutters, a duct between said inlet chamber and said cylinder, a check valve in said duct responsive only to predetermined abnormal pressure in said chamber to open said duct for flow, ports in said duct at opposite sides of said check valve, a control valve movable on said duct and having ports, thermostat means responsive to the temperature of the cooler discharge flow for setting said control valve to shut off said duct ports or to register its ports with the duct ports to define a by-passageway around said check valve for flow into the cylinder when said check valve is closed for outward movement of the piston to move the shutters to closing position under pressure less than that necessary to open said check valve.

6. A controlling structure for an internal combustion engine oil cooler having shutters thereon, comprising a housing having an inlet chamber for receiving the oil from the engine for delivery to the cooler, a cylinder having a piston connected with the cooler shutters for operation thereof, spring means tending to move said piston

inwardly for opening movement of the shutters, a valve member in the form of a bar between said inlet chamber and said cylinder and having a bore therethrough for flow of oil from the chamber to the cylinder, a spring pressed check valve in said bore closing said bore against flow therethrough under normal fluid pressure in said inlet chamber but being responsive to predetermined increased pressure to open said bore for flow of fluid to the cylinder to effect outward movement of the piston for closing movement of the shutters, ports on opposite sides of said check valve extending from said valve bar bore to the outer side thereof, a valve collar rotatable on said valve bar and having ports for registering with said valve bar ports for flow of oil from the inlet chamber into said cylinder when said check valve is closed, a thermostat subjected to the temperature of the discharged oil from the cooler for setting said valve collar in accordance with variations in temperature to open or close said valve bar ports, and a connection between said piston and valve bar effective upon axial movement of said piston to rotate said valve bar to move its ports into or out of registration with said collar ports for continuation of flow or stoppage of flow into the cylinder while said check valve is closed until said thermostat operates said collar for setting of its ports for reclosure or reopening of said valve bar ports.
